UNITED STATES PATENT OFFICE.

ALPHONS RAPPENECKER, OF BREMEN, GERMANY.

TRANSMITTER FOR WRITING-TELEGRAPHS AND THE LIKE.

1,135,393.

Specification of Letters Patent.

Patented Apr. 13, 1915.

Application filed October 27, 1913. Serial No. 797,638.

To all whom it may concern:

Be it known that I, ALPHONS RAPPENECKER, director, a subject of the German Emperor, residing at Bremen, Rolandhaus, Am Brill 5 8-12, Germany, have invented certain new and useful Improvements in Transmitters for Writing-Telegraphs and the like; and I do hereby declare the following to be a full, clear, and exact description of the invention, 10 such as will enable others skilled in the art to which it appertains to make and use the same.

This invention relates to a transmitter device for copying and like telegraphic apparatus in which the movement of the writing pencil is resolved into two coördinate directions and converted into changes of electric resistance. In these transmitter devices the pencil is mounted on an oscillating lever, the 15 pivot pin of which is secured to a carriage adjustable in the direction of the abscissæ. In order to convert the oscillating movements of the pencil into the direction of the ordinates, the pencil is also rectilinearly 20 guided in the direction of the ordinates, and to equalize the deviations between this rectilinear guide and the arc described by the pencil about its pivot pin, the pivot pin of the pencil lever must also allow of a movement of its own in the abscissa direction, 25 on the carriage or slide adjustable in the direction of the abscissæ. The arrangement must be however made in such a manner that the said mobility of the pivot pin of the pencil lever in the direction of the abscissæ relatively to the slide should not be converted 30 as an abscissa movement into changes of resistance, but that only the oscillating movements converted into the ordinate direction, 35 should produce changes of resistance.

According to this invention, the movements of the pivot pin of the pencil lever relatively to the carriage in the direction of the abscissæ are obtained by connecting the 40 pencil lever to the carriage by means of a lever pivoted to the latter. This arrangement gives a specially easy mobility of the movement for equalizing between the arc described by the pencil and the ordinate movement representing a chord of the said 45 arc.

A construction according to this invention is illustrated in the accompanying drawing in Figure 1 in side elevation, partly in section, and in Fig. 2 partly in a horizontal sec-

tion on line 2—2 of Fig. 1, and partly in plan.

The pencil *a* which writes on the table *u*, is mounted on a lever *b* connected to the part *c* by a spring blade *y* which allows the pencil lever *b* and the pencil *a* to be raised and depressed. The writing table plate *u* rests on a casing *w* which carries by means of a plate *x*, the carriage guides *n* and *j*. Rods *z* and *z'* secured to the frame, carry a resistance *k* consisting of numerous windings. 60 65

The carriage itself comprises a longitudinal rod *l* to which is secured in front a transverse spindle with rollers *o*. The rod *l* carries at its rear end a head or block *g* connected by lateral lugs *h* to a sleeve *i* which can slide in the longitudinal direction on the guide *j*. The rollers *o* travel between the rails *n* and the contact rods *m* situated above. To the sleeve *i* is connected a contact *t* which, during the longitudinal movement of the carriage, switches in or out in a well known manner a larger or smaller number of the windings of the resistance *k*, and in that way produces changes of resistance corresponding to the abscissæ movement of the pencil. 70 75 80

To the part *g* of the carriage is pivoted a pair of levers *f* rotatably connected to a sliding member *f'* vertically adjustable on 85 the bracket *e*. The bracket *e* is used as a holder for the pencil lever which is pivoted with the stem or pillar *c* between pins of the bracket *e*. To the stem *c* is connected a rod *d* which is parallel to the pencil lever 90 *b* and guided at the front end by means of a member *v* pivoted by a vertical pin and sliding on a straight bar *q* secured by means of the small brackets *p* to the carriage in transverse direction. On the sliding member *v* 95 is mounted a contact *s* sliding along the resistance *r* consisting of numerous windings and thus producing in well known manner changes of resistance during the ordinate movement. 100

In writing with the pencil *a* all the movements of the pencil in the direction of the abscissæ, are transmitted by means of the parts *b* *c* *d* *q* *p* to the carriage, and therefore to the contact *t*, and in that way 105 changes of resistance corresponding to the movement in the direction of the abscissæ are produced. The rod *d* participates however in the oscillating movements of the pencil *a* as the said rod is rigidly connected 110

in the transverse direction to the writing lever by means of the part *c*. As however the front end of the rod *d* is guided by means of the sliding member *v* in a rectilinear manner on the rod *q*, the deviation between the said rectilinear guiding and the arc movement of the pencil *a* must be equalized. This is effected by the pencil lever *b* together with the parts *c* and *d* being connected to the carriage not directly but by means of the oscillating lever *f*. Consequently, and as the rod *d* is rotatably connected to the sliding member *v* when the pencil *a* oscillates, the pencil holder *c*, 15 can make a movement in the direction of the abscissæ relatively to the carriage, corresponding to the difference between the arc of oscillation of the pencil *a* and the chord determined by the guide *q*. This movement, 20 although it takes place in the direction of the abscissæ, is not converted into a change of resistance at the resistance *k*, as the sleeve *i* with the whole carriage, does not then make any movement. During the 25 oscillation of the pencil *a* about its axis, there only takes place therefore a conversion of the ordinate movement into a change of resistance. The movement of the pencil lever relatively to the carriage takes place 30 easily in the present arrangement, as only

the lever *f* has to be oscillated, which together with the part *f'* has merely to make short sliding movements on the bracket *e* in the vertical direction.

Having now particularly described and 35 ascertained the nature of my said invention and in what manner the same is to be performed, I declare that what I claim is:—

In a transmitter for copying and like telegraphic apparatus, the combination with a 40 movable carriage, a pivotally mounted pencil lever, an electric resistance varied by unitary movements of the pencil lever and carriage in the direction of the abscissæ, and a second electric resistance associated with the 45 pencil lever and carriage disposed substantially at right angles to the first-named resistance and varied by movements of the pencil in the direction of the ordinates, of a link pivotally associated with the pencil lever near its axis of oscillation and pivotally connected with the carriage, for the 50 purpose described.

In testimony whereof I have affixed my signature, in presence of two witnesses.

ALPHONS RAPPENECKER.
